UNITED STATES PATENT OFFICE.

RASMUS N. JENSEN, OF SALT LAKE CITY, UTAH.

LATHING SHEET.

Application filed November 22, 1926. Serial No. 150,076.

This invention relates to a sheet lathing or foundation upon which is imposed the interior plaster finish of buildings, and has for its object to provide a simple and efficient structural formation of a lathing sheet capable of easy and economical production and which while affording an efficient foundation for the plaster, requires but a minimum amount of the same in forming the necessary backing and which has novel means thereon to provide the necessary clinching bond between the plaster and the lathing sheet.

Another important object of the invention is to provide a sheet lathing or foundation of this nature which will eliminate the great waste of material incident to the pushing of plaster on ordinary lathing now in common use wherein a certain amount of the plaster is forced between the laths to form keys.

Another very important object of the invention lies in the provision of a lathing sheet which may be conveniently and readily rolled up into a compact bundle for shipping and storing purposes and from which roll it may be easily and quickly unwound for application to the studding of the building.

With the above and numerous other objects in view as will appear as the description proceeds, the invention resides in certain novel features of construction, and in the combination and arrangement of parts as will be hereinafter more fully described and claimed.

In the drawings:

Figure 1 is a plan view of a lathing sheet applied to studding in accordance with the principles of my invention.

Fig. 2 is a detail section taken therethrough substantially on the line 2—2 of Fig. 1.

Fig. 3 is a perspective view showing a portion of one of the lath strips before the same is perforated.

Fig. 4 is a fragmentary plan view of a lathing sheet showing a modified form of the invention.

Fig. 5 is a detail section taken therethrough substantially on the line 5—5 of Fig. 4.

Fig. 6 is a fragmentary enlarged plan view of the rear surface of the sheet shown in Fig. 4.

Referring to the drawing in detail and

particularly Figs. 1 to 5 inclusive, it will be seen that the numerals 5 denote vertically disposed studdings that are commonly provided in the ordinary building structure to form the walls in the interior and exterior of rooms, buildings, and the like. The numeral 6 denotes a sheet of flexible material preferably paper or cardboard which is adapted to be produced in rolls and has disposed transversely thereof a plurality of lath strips 7 fixed thereto by means of clips 8 or in any other suitable or preferred manner. Each lath strip is provided along its median longitudinal dimension with an outwardly struck bead 9 and to each side of the bead the strip is punched to form openings having annular collars 10 with jagged edges 11. When the sheet 6 is applied to the studding 5 as is shown in Fig. 1 the lath strips 7 extend horizontally in spaced parallelism and the sheet 6 will be cut off the desired length and nailed to the studding or otherwise secured thereto. The plaster is applied directly to this lathing sheet or foundation and sufficient of the plaster will pass into the collars so that the plaster when set will be sufficiently locked to the sheet 6 for all practical purposes.

In Figs. 4, 5 and 6 I have shown another embodiment of the invention wherein the sheet 6' is formed with pairs of slits 12, and in the preferred of this modification the series of slits 12 and strips 13 therebetween will have an alternated or staggered relationship to each other with their ends terminating short of each other as distinguished from an overlapping relationship. The lath strips 7 are identical in formation with those previously described and extend through the slits 12 in behind strips 13 so that no further fastening elements are necessary. This modification will be used in identically the same manner as the embodiment described in the beginning.

From the above detailed description it will be seen that this lathing sheet or foundation is much more quickly and cheaply nailed in place than the ordinary laths each of which has to be handled separately and nailed in place separately in a certain predetermined spaced relation. This lathing sheet or foundation enables a smoother wall to be formed which will prove just as durable and strong as the ordinary plaster wall. The sheets may be manufactured in rolls at a relatively low cost and are capable of being

easily and conveniently handled in shipments and take up a minimum amount of room in storage. It is to be further noted that the jagged edged collars enable the plasterer to 5 obtain the necessary clinching grip.

It is thought that the construction, utility, and advantages of this invention will now be clearly understood by those skilled in this art without a more detailed description 10 thereof. The present embodiment of the invention has been disclosed in detail merely by way of example since in actual practice it attains the features of advantage enumerated as desirable in the statement of the 15 invention and the above description. It will be apparent that changes in the details of construction, and in the combination and arrangement of parts or in the means or method of fastening strips to sheet may be

resorted to without departing from the spirit 20 or scope of the invention as hereinafter claimed or sacrificing any of its advantages.

Having thus described my invention what I claim as new is:

A lathing for plastering comprising a 25 sheet of flexible paper, or any other suitable material, transverse lath strips arranged on one face of the sheet, and means for holding said strip in spaced parallel relationship, each strip being of an elongated formation 30 having a longitudinally extending outwardly struck bead along its median longitudinal dimension, and portions alongside of the bead being struck therefrom to form jagged edged collars. 35

In testimony whereof I affix my signature.

RASMUS N. JENSEN.
